UNITED STATES PATENT OFFICE.

TRACY L. PAYNE, OF MILWAUKEE, WISCONSIN, ASSIGNOR TO THE NATIONAL ELASTIC NUT COMPANY, OF SAME PLACE.

DESIGN FOR A SPLIT NUT.

SPECIFICATION forming part of Design No. 30,898, dated May 30, 1899.

Application filed March 30, 1899. Serial No. 711,166. Term of patent 14 years.

To all whom it may concern:

Be it known that I, TRACY L. PAYNE, a citizen of the United States, residing at Milwaukee, in the county of Milwaukee and State 5 of Wisconsin, have invented and produced a new and original Design for a Split Nut; and I do hereby declare the following to be a full, clear, and exact description of the same, reference being had to the accompanying drawings, forming a part thereof.

In the said drawings, Figure 1 is a perspective view, and Fig. 2 is a plan view, of a split nut embodying my new design.

My design relates to the new and original 15 shape or configuration of the article.

The leading or essential feature consists in the unitary design for a split nut made the subject of illustration, comprising the shape 20 of the upper and lower portions of the nut above and below the split or line of separation, as hereinafter more particularly described.

As shown in the drawings, *a* *b* represent two adjacent faces of a hexagon nut, through 25 which faces and the balance of the nut back of them to the bore *c* the described split or separation occurs. This line of separation extends downward from the top of the nut to a point above the horizontal center, from

the bore to and through one face of said nut, 30 and thence in a rounded line to said horizontal center, along said horizontal center through the adjacent face of the nut, thence in a rounded line to a point below the said horizontal center, and thence down to and through 35 the bottom of the nut, so that the face *a* has its upper right-hand corner or portion separated therefrom and face *b* has its lower left-hand corner or portion separated therefrom, the integral or remaining part of each of said 40 two faces comprising a vertical and a horizontal projecting portion rounded at the point of union of the two portions, all the faces of the said nut being vertical and of equal size and all of said faces, except faces *a* and *b*, specified, being free from any interruption or line 45 of separation.

Having thus described my invention, what I claim as new, and desire to secure by Letters Patent, is—

The design for a split nut, substantially as herein shown and described.

In testimony whereof I affix my signature in presence of two witnesses.

TRACY L. PAYNE.
